FILTER

Lloyd W. Watson, Oakland, Calif., assignor to
 Oliver United Filters Incorporated, San Francisco, Calif., a corporation of Nevada

Application August 20, 1935, Serial No. 37,003

3 Claims. (Cl. 210—195)

This invention relates in general to filters, and particularly to a locking strip for locking the filter medium of a filter to its frame or support, such as the division strip of a rotary drum filter.

5 The object of the invention is the provision of a zig-zag or corrugated resilient metal locking strip by means of which the filter medium of the filter may be detachably secured or locked within a channel formed in the frame of a filter or 10 in the division strip of a rotary drum filter.

The invention possesses other advantageous features, some of which with the foregoing, will be set forth at length in the following description where that form of the invention which has 15 been selected for illustration in the drawing accompanying and forming a part of the present specification is outlined in full. In said drawing, one form of the invention is shown, but it is to be understood that it is not limited to such form, 20 since the invention as set forth in the claims may be embodied in a plurality of forms.

Referring to the drawing:

Figure 1 is a side elevation of a zig-zag locking strip embodying the objects of my invention.

25 Figure 2 is a side elevation of a modified form of zig-zag locking strip.

Figures 3a to 3e inclusive show five different cross sections in which the zig-zag strips shown in Figures 1 and 2 may be made.

30 Figure 4 is a cross section taken through the division strip of a rotary drum filter, and showing one application of my invention.

Figure 5 is a partial cross section of the frame of a leaf filter showing another application of 35 my invention.

The zig-zag strip shown in Figure 1 may be considered as defined by a number of consecutive oppositely pitched portions 1 and 2 whose junctions form protrusions or knobs 3 and 4.

40 The modified zig-zag locking strip shown in Figure 2 is formed by a number of aligned interrupted straight portions 5 joined by means of protrusions or knobs 6.

Either form of locking strip may be made of 45 any desired cross-section such as, for example, illustrated in Figures 3a and 3e inclusive.

In Figure 4 the locking strip of the form illustrated in Figure 1 is shown in conjunction with a division strip 7 such as is used on a rotary drum 50 filter. The division strip 7 is provided with an undercut or trapezoidal channel 8 within which the filter medium 9 is locked by the action of the knobs 3 and 4 of the locking strip. Although the locking strip as shown in Figure 4 is of general

trapezoidal cross-section to conform to the trapezoidal channel in the division strip it has been found that other cross-sections will serve equally well.

In Figure 5, the locking strip of the form illustrated in Figure 2 has been shown as applied to a circular filter leaf comprising a frame member 11 provided on its inner periphery with a channel 12 for accommodating the usual drainage member and supporting screens 13 and on either 10 side with opposed undercut channels 14 in which the filter medium 15 is locked by the action of the locking strip. It should be particularly noted that the interrupted straight portions 5 of the locking strip face inwardly and form extended 15 flat bearings which clamp the filter medium 15 against the inner walls of the channel 14. This feature is of considerable importance for it has been found that if the filter cloth is stretched too tightly over the frame the point contacts of 20 the knobs 3, 4 and 6 have a tendency to rupture the filter medium whereas the extended surface contacts of the straight portions do not.

The locking strips shown in Figures 1 and 2 provide means whereby a filter medium may be 25 positively and detachably secured within a channel formed in a supporting frame or member at predetermined spaced intervals and may be used in their generally straight form as shown in connection with Figure 4 or curved as shown in connection with Figure 5.

The locking strip is inserted into its channel by first forcing one end into the channel and then progressively forcing the remainder into position. The reverse procedure is followed in disengaging 30 the strip.

I claim:

1. In a filter: a base member; a channel formed in said base member; a section of filter medium disposed within said channel; and a zig-zag locking strip resiliently engaged between the walls of said channel and said filter medium.

2. In a filter: a base member having a channel therein; a fabric lining said channel and a zig-zag locking strip resiliently engaged within said 45 channel and contacting said fabric at spaced intervals.

3. In a filter: a base member having a channel and a resilient locking strip formed of extended interrupted flat surfaces joined by outwardly extending knobs resiliently engaged with 50 in said channel.

LLOYD W. WATSON.
